UNITED STATES PATENT OFFICE.

CARL MARTINI, OF BERLIN, GERMANY; MARIE MARTINI, EXECUTRIX OF SAID CARL MARTINI, DECEASED, ASSIGNOR TO MARTINI & HÜNEKE MASCHINENBAU-AKTIEN-GESELLSCHAFT, OF BERLIN, GERMANY, A CORPORATION OF GERMANY.

APPARATUS FOR CONVEYING LIQUID FUEL.

1,132,482.

Specification of Letters Patent. Patented Mar. 16, 1915.

Application filed September 8, 1909. Serial No. 516,974.

To all whom it may concern:

Be it known that I, CARL MARTINI, a subject of the German Emperor, and resident of Berlin, Germany, have invented certain 5 new and useful Improvements in Apparatus for Conveying Liquid Fuel, of which the following is a specification.

The conveyance of inflammable liquids (such as gasoline) through pipes has been 10 accomplished, for the sake of safety, in the presence of an inert gas, as described in Letters Patent of the United States No. 871353, granted to Hermann Hüneke and myself on Nov. 19, 1907. As an inert gas, I have 15 employed in practice a gaseous mixture resulting from a thorough combustion (excluding any excess of air) of an inflammable or explosive mixture, which may be of substantially the same character as the 20 one fed to the cylinder of an automobile engine. The plant comprises a receptacle to which the inert gas is supplied by a pump, while in some cases another pump forces the liquid from said receptacle to the place 25 of discharge or use. Obviously there is some danger of the gas pump continuing to operate after the production of inert gas has ceased, and in this event the pump would supply air instead of inert gas to the 30 receptacle. When a pump is used to withdraw the liquid from the receptacle, it might happen that the gasometer (in which the gas is stored on its way from the producer to the receptacle) being empty a reduction of pressure would take place in the 35 receptacle, which latter owing to the pressure of the surrounding air, might readily become leaky and admit atmospheric air. In either event, the inflammable liquid 40 would come in contact with air, and this I desire to avoid.

A typical example of an apparatus embodying my present invention is shown in the accompanying drawings, in which—

45 Figure 1 is a general view of the plant, with parts in section, and Fig. 2 is a side elevation, with parts in section, showing chiefly the motor and the gas producer.

Briefly described, the apparatus comprises 50 a producer of inert gas, together with means for feeding the gas and liquid, the operation of one or both of said means, being dependent upon that of the producer. The preferred embodiment of this invention

involves the use of an internal combustion 55 engine operating said feeding means (generally pumps) and governed by the operation of the gas producer.

In the drawing, 1 indicates a chamber in which the explosive mixture admitted 60 through the pipe 2 is thoroughly consumed at 1^a under exclusion of air (except that contained in the mixture itself). The inert gas resulting from this combustion passes through the suction pipe 3 to the gas 65 pump 4 and thence through a pipe 5 to the gasometer 6. From the gas chamber of the gasometer the inert gas passes through a pipe 7 secured to the cover 8 of the receptacle 9. The inflammable liquid (for instance gasoline) is taken through a suction pipe 10, reaching close to the bottom of the receptacle 9, to the liquid pump 11 and then passes through the pipe 12 to the place 75 of use.

An internal combustion motor 13, which operates the pumps 4 and 11 as will be described presently is dependent upon the operation of the producer 1. This dependence may be secured in various ways, 80 for instance by using part of the explosive mixture fed to the producer as the working medium for the engine, as indicated in Fig. 2, where a branch pipe 24 leads from the producer 1 to the mixing 85 chamber 25 and to the inlet valve of the engine 13, or by utilizing the heat generated in the producer chamber for igniting the fuel in the engine as by having the ignition tube 26 of the engine projected into the combustion chamber of the producer 1 and exposed to the flame 1^a. These or other expedients may be used singly or jointly. It will thus be understood that if for any reason the mixture fed to the producer 1 should 90 not be properly proportioned and therefore lack explosive qualities, the motor 13 would stop as it would receive an inefficient fuel mixture. Similarly, if the flame within the producer 1 should accidentally become extinguished, thus interrupting the formation of inert gas, the motor would stop since there would be no ignition.

The driving of the pumps 4 and 11 from the motor 13 may be accomplished in any 105 suitable manner, for instance by a belt 15 engaging the fly wheel 14 and a pulley 17 upon a countershaft 16. This shaft also car-

ries pulleys 18 and 19 from which belts 20 and 21 lead to the pulleys 22 and 23 on the shafts of the pumps 4 and 11 respectively.

The countershaft 16 with its connections 5 may be termed means for actuating the device (such as the pump 4) for feeding the gas generated in the producer, and may also be termed means for actuating the device (such as the pump 11) for withdrawing 10 liquid from the receptacle. The motor thus forms a controller, influenced by the producer's action, for governing the operation of said means.

It will therefore be seen that in the form 15 of my invention illustrated by the drawing, any interruption in the production of the inert gas will cause an automatic stoppage of the gas pump 4 and of the liquid pump 11, thus avoiding the sources of danger hereinbefore mentioned.

20 Certain features shown in my present application are claimed generically in my application Serial No. 516976 filed concurrently herewith.

25 The operative connection between the pumps 4 and 11 (formed by the shaft 16 and belts 20, 21) is a decided advantage in that it insures the preservation of a proper pressure in the receptacle 9 whenever liquid is 30 withdrawn therefrom through the pipe 10. For, as soon as the pump 11 is operated to withdraw liquid from said receptacle, the pump 4 is also operated to feed the proper amount of inert gas into said receptacle 35 through the pipe 7, thus maintaining a practically constant gas pressure in the receptacle.

I claim as my invention:

40 1. The combination of a gas producer, means for leading an explosive mixture thereto, a device for feeding the burned gas from the producer, an internal combustion motor for actuating said device, and means for leading to said motor, as its working medium, a portion of the said explosive mixture.

45 2. The combination of a gas producer, means for leading an explosive mixture thereto, a device for feeding the burned gas from the producer, an internal combustion motor, the ignition of which is controlled by the operation of the producer, for actuating said device, and means for leading to said motor, as its working medium, a portion of 50 said explosive mixture.

55 3. The combination of a gas producer, a device for feeding the gas produced therein,

means for actuating said device, and a controller, influenced by the producer's action, for governing the operation of said means. 60

4. The combination of a gas producer, a suction device, connected with the outlet of the producer, for withdrawing gas therefrom and feeding it forward, means for actuating said device, and a device controlling 65 said actuating means, said controlling device being exposed to, and operated by, the heat of the producer.

5. The combination of a gas producer, a suction device, connected with the outlet of 70 the producer, for withdrawing gas therefrom and feeding it forward, means for leading an explosive mixture to said producer, an internal combustion motor for actuating said suction device, and means 75 for leading to said motor, as its working medium, a portion of the said explosive mixture.

6. The combination of a gas producer, a suction device, connected with the outlet of 80 the producer, for withdrawing gas therefrom and feeding it forward, an internal combustion motor for actuating the said device, and an igniter for said motor, which igniter extends into the producer so as to be 85 exposed to the heat thereof.

7. The combination of a gas producer, a suction device, connected with the outlet of 90 the producer, for withdrawing gas therefrom and feeding it forward, means for leading an explosive mixture to said producer, an internal combustion motor, the ignition of which is dependent upon the operation of the producer, for actuating said suction device, and means for leading to said 95 motor, as its working medium, a portion of the said explosive mixture.

8. The combination of a gas producer, a device for feeding gas from the producer, an internal combustion motor for actuating 100 said device, and an igniter for said motor, controlled by the heat of the producer.

9. The combination of a gas producer, a device for feeding gas from the producer, an internal combustion motor for actuating 105 said device, and an igniter for said motor, exposed to the flame of the producer.

In testimony whereof I have hereunto set my hand in the presence of two subscribing witnesses.

CARL MARTINI.
